G. E. ALPHIN

WINDOW FIXTURE

Filed March 17, 1927

UNITED STATES PATENT OFFICE.

GILBERT E. ALPHIN, OF MOUNT OLIVE, NORTH CAROLINA.

WINDOW FIXTURE.

Application filed March 17, 1927. Serial No. 176,158.

The invention relates to improvements in window fixtures designed for supporting shade rollers, curtain rods and drapery rods, and one object is to provide a fixture which will be exceptionally simple and inexpensive, yet will be efficient and very desirable.

Another object of the invention is to provide supports for the drapery rod of novel and advantageous construction, which construction may well be formed by merely bending two metal strips upon transverse lines.

Another aim is to make novel provision for holding the shade roller in place and preventing its flat stub from accidentally disengaging from the co-acting supporting bracket, in case the shade should slip from the hand of a person adjusting it and rapidly wind to the maximum, the construction however being such that said stub may be readily inserted into or disengaged from a slot of the bracket, when the shade roller is being positioned for use or removed, as occasion may demand.

A still further aim is to provide a drapery supporting rod with novel clamping means at its ends for holding the edges of the drapery.

With the foregoing in view, the invention resides in the novel subject matter herein-after described and claimed, the description being supplemented by the accompanying drawing.

Fig. 1 is a plan view of the invention applied to a window frame, of double form.

Fig. 2 is a side elevation of the parts shown in Fig. 1.

Figs. 3 and 4 are longitudinal sectional views on the correspondingly numbered lines of Fig. 1.

Fig. 5 is an enlarged transverse section on line 5—5 of Fig. 1.

Fig. 6 is a disassembled perspective view of one of the drapery rod supporting brackets, these brackets being also instrumental in supporting the shade roller and the curtain rod.

Fig. 7 is a view similar to a portion of Fig. 4 but illustrating the manner in which the shade roller may be engaged with or disengaged from its supporting brackets.

In the drawing above briefly described, the numeral 8 denotes a plurality of brackets for supporting two shade rollers 9, two curtain rods 10, and an extensible and retractable drapery rod 11. When the fixture is to be

used on a double window, such as that shown, three of the brackets 8 will be necessary to support the two shade rollers 9 and the two extensible and retractable curtain rods 10, 60 but the drapery rod 11 is extensible to such a length that only one of these rods is necessary. When the fixture is to be used on a single window, only two of the brackets 8 will be needed and said brackets will then 65 engage opposite ends of the shade roller and the curtain rod, and the drapery rod 11 will be retracted to the desired length, or a shorter rod used.

As the construction of all of the brackets 70 8 is identical, only one will be described in detail. This bracket, in the preferred form of construction, is formed from a single metal strip bent upon transverse lines to provide a pair of spaced parallel arms 12 connected at one end by an attaching plate 13, the free ends of said arms being bent inwardly toward each other as at 14. The plate 13 is formed with an opening 15 to receive an attaching screw or other fastener 16, 75 and the arms 12 are each formed with an opening 17 and a vertically elongated slot 18. The openings 17 are to receive the curtain rod 10 whose ends may be provided with knobs 19 to prevent accidental withdrawal. 80 The slots 18 are intended to receive either the cylindrical journal 20 at one end of the roller 9, or the usual flat stub 21 at the opposite end thereof, and when applying or removing the shade roller 9, one of the brackets 8 may 90 be turned about the screw 16 as a pivot, from its normal position, to an inclined position, so that the stub 21 may readily pass into or out of the slot 18, the journal 20 being then engaged with the corresponding slot of another of the brackets 8, as will be clear from Fig. 7.

The inwardly turned ends 14 of the arms 12, are removably received in the opposite ends of a flat metal sleeve 22, which sleeve 100 rigidly carries a supporting hook 23 for the drapery rod 11. By preference, the sleeve 22 and its hook 23 are formed by bending a single metal strip upon transverse lines, as will be clear from Figs. 5 and 6.

When driving the fastener 16, in order that it may be made more accessible, the arms 12 may be sprung apart, permitting the sleeve 22 to be disengaged from the arm ends 14, and after driving of said fastener, 110 said arm ends may be re-engaged with the sleeve, so that the bracket effectively sup-

ports the hook 23 in position to engage the rod 11.

The rod 11 lies removably within the hooks 23 of the brackets 8 and is effectively supported by them. This rod may be formed of flat strip metal or may be of tubular form, as desired, and its ends may be extended any desired distance beyond the brackets 8.

10 In the preferred construction, the ends of the rod 11 are bent rearwardly as at 24, and these rearwardly bent ends are inwardly and forwardly folded upon themselves to provide forwardly directed spring fingers 25. The edge portions of the drapery turn rearwardly, of course, toward the window frame and said edges will be tenaciously held between the fingers 25 and the outlying portions of the rearwardly bent ends 24.

15 It will be seen from the foregoing, that a very novel construction and relation of parts has been provided for carrying out the objects of the invention, and while the details herein disclosed are preferable, it will be understood that slight variations may be made within the scope of the invention as claimed.

I claim:

30 1. A rod support comprising attaching means, two spaced arms projecting in the same direction therefrom and having their free ends turned inwardly toward each other, a sleeve receiving said inturned arm ends, and a rod-supporting hook carried by said sleeve.

35 2. A rod support comprising a strip of metal bent on transverse lines to provide two spaced arms extending in the same direction and an attaching plate connecting said arms at one end, said plate having a

fastener-receiving opening, the free ends of said arms being bent inwardly toward each other, a sleeve receiving said inwardly bent arm ends, and a rod-supporting hook carried by said sleeve. 45

3. A rod support comprising attaching means, two spaced arms projecting in the same direction therefrom and having their free ends turned inwardly toward each other, and a metal strip bent upon transverse lines to provide a flat sleeve and a rod-supporting hook at the exterior thereof, said sleeve receiving said inturned arm ends. 50

4. A rod support comprising a strip of metal bent on transverse lines to provide two spaced arms extending in the same direction and an attaching plate connecting said arms at one end, said plate having a fastener-receiving opening, the free ends of said arms being bent inwardly toward each other, and a second metal strip bent upon transverse lines to provide a flat sleeve and a rod-supporting hook at the exterior thereof, said sleeve receiving said inturned arm ends. 55

5. A shade roller supporting means comprising two brackets one of which is formed with an opening to receive the cylindrical journal at one end of the roller, the other bracket having a vertical slot closed at both ends for reception of the flat stub at the other end of the roller, and mounting means for said other bracket permitting turning thereof from a normal position in a vertical plane, to an inclined position when said flat stub is being inserted into or removed from said slot. 65

In testimony whereof I have hereunto affixed my signature.

GILBERT E. ALPHIN.
